UNITED STATES PATENT OFFICE.

LAZARD KAHN, OF HAMILTON, OHIO, ASSIGNOR TO F. & L. KAHN & BROS.,
OF SAME PLACE.

DESIGN FOR A FOOT-RAIL FOR STOVES.

SPECIFICATION forming part of Design No. 29,884, dated December 27, 1898.

Application filed November 10, 1898. Serial No. 696,085. Term of patent 14 years.

To all whom it may concern:

Be it known that I, LAZARD KAHN, a citizen of the United States, residing at Hamilton, Butler county, Ohio, have invented and produced a new and original Design for a Foot-Rail for Stoves, of which the following is a specification, reference being had to the accompanying drawings, forming part thereof.

Figure 1 is a perspective view of a foot-rail, showing my new design; and Fig. 2 is a sectional view taken on the line *a* of Fig. 1.

As shown in the drawings, the leading or material feature of my design consists of a top ring *A*, having an upper edge *B*, in con-

junction with a base-rail *C*, of larger diameter ¹⁵ than the top ring and disposed below and concentric with the top ring, the two rings being integrally joined by a band *D*, extending from the top ring to the base-rail.

Having described my invention, what I ²⁰ claim as new, and desire to secure by Letters Patent, is—

The design for a foot-rail for stoves, as herein shown and described.

LAZARD KAHN.
